Attorney.

UNITED STATES PATENT OFFICE

1,928,666

ADJUSTABLE ANTIGLARE DEVICE

Edward M. Keller, Detroit, Mich.

Application May 16, 1932. Serial No. 611,514

6 Claims. (Cl. 2—12)

It is obviously a well known fact that in driving an automobile at night the glare from the lights of the oppositely moving vehicle on the highway has a most blinding effect upon the driver's eyes, 5 and quite frequently very serious accidents occur as result of this menace to motorists. The invention is as equally advantageous in effectively shielding the eyes from the bright rays of the sun when traveling in a direction toward the same. 10 This is of course a condition that confronts every motorist as well as that of the glare of the lights of the oppositely moving vehicles.

My invention primarily is designed for the purpose of completely overcoming this difficulty by 15 providing a device to be worn upon the head while night driving, and which is adjustable in such a manner as to render the same susceptible to the proper focus to suit the eyes of any person adapted to the use of the invention.

20 One of the advantages of the invention is that it is very light in weight and is not burdensome to wear. It may be attached to the head quickly and likewise removed at will, when not in use.

The invention is designed to shield the eyes 25 from the bright center of the lights of the oppositely moving vehicle in a manner so as to obviate reflection of the light upon the metal of the device, thus making it restful upon the eyes regardless of the period of time it is being in continuous 30 use.

My invention possesses further advantages, all 35 of which will be clearly revealed during the course of the following detailed description, illustrated throughout the accompanying drawing, and more fully pointed out in the appended claims.

With reference to the drawing:

Figure 1 is a complete underneath view of the 40 invention and showing the same in a maximum opened position; also illustrating the optical vision through the device consistent with this particular adjustment.

Figure 2 is a top plan view of the complete invention showing the same attached to the head 45 for normal use, and broken as indicated; the invention is also shown in this view in a maximum closed position.

Figure 3 is a front elevation of the device in a closed position.

Figure 4 is a partial rear elevation of the invention.

Figure 5 is a sectional view taken substantially upon line 5—5 of Figure 3.

The invention comprises two units, each formed 55 of a single sheet of metal and having top portion 1 and opening in the front thereof as at 2, also fin-

3 formed at right angles thereto and being a part of the unit. It is also seen that the rear edge of portion 1 is doubled back as at 4 to obviate the sharp edge of the metal adapted to contact the head when the device is adjusted as in Figure 1. 60

The aforesaid units are also provided with vertical outer wall 5, and inner wall 6 as indicated.

Framework 7 is provided and is composed of a single portion of wire as shown. The said framework having portion 7A formed as in Figure 1, 65 which is adapted to conform to the nose, similar to that of spectacles. Sheet metal member 8 has outwardly turned ears 9, in opposed relation and adapted to be pivotally secured to framework 7 by rivets 10 respectively. 70

Both units as previously described are adjustable relative to member 8 and as illustrated in Figures 1 and 2, in the following manner:

Referring more particularly to Figures 1, 2 and 5, it is observed that member 8 has portion 11 75 formed thereon and lever 12 pivotally secured to the same by rivet 13 where indicated, and links 14 pivotally connected to the said lever by rivets 15 respectively, and the opposite end of the said links pivotally connected to portion 1 of the principal 80 units of the device respectively, by rivets 16. Also upturned ears 17 formed upon the said lever to form stops for the same.

In Figure 3 it is seen that the metal forming opening 2 in the principal units is deflected inwardly and forming thereby respective pins 18 as shown. 85

Referring to Figure 4 it is also observed that shield 19 is formed integral with each of the principal units of the device. 90

In Figure 2 a metal strap 20 is provided, one end of which is pivotally secured to portion 11 of member 8 by rivet 13, and the opposite end thereof secured to flexible band 21. The purpose of the said strap is to conform to the top 95 of the head A and supporting the device in a manner so as to relieve pressure of the same through portion 7A of framework 7, upon the nose. It is further revealed that the ends of band 21 are connected to framework 7 as at 21A. 100

In Figure 5 the lower portion of member 8 is formed as at 22 in order to form a stop for the nose contacting portion 7A of framework 7 as indicated.

Framework 7 is substantially reinforced by 105 metal 23 as shown in Figure 4.

With reference to Figure 1 human eyes B are indicated and the passage of the optical vision through the device in a maximum opened position is shown by the dotted lines in this view, and 110

obviously from this illustration it is readily understood that the same satisfactory vision is possible through the device when the same is adjusted to any position ranging between that shown in Figure 1 and that of Figure 2. Shields 19 prevent the bright light from blinding the eyes, while fins 18 prevent the light from reflecting upon the inner surface of the metal walls 5.

Due to the particular construction of my device 10 I have carefully obviated every possible glare or bright reflection upon any portion thereof, and as the design of the invention is a very simple one the manufacturing cost of the same would obviously permit a selling price that would be 15 within the reach of every one.

It is suggested that virtually the entire device 20 be made of sheet aluminum owing to the durability and lightness in weight of this metal, however any light weight material may be used for this purpose.

It is apparent that I have hereinabove described, with the aid of the accompanying drawing, one precise embodiment of my invention, however I reserve the right to make certain minor 25 changes in the construction or the design thereof, in the event that this condition presents itself during any probable further development of the same for the market, but in any eventuality a departure from the general principle as disclosed 30 would be consistently avoided.

Having thus described my invention, what I claim as new is:

1. In an adjustable anti-glare device, a pair 35 of oppositely disposed units for the same, the said units having a top portion, outer and inner depending vertical walls and front portion, vision passage within the said front portion, also a fin formed of and at right angles to each of the said units and extending outwardly therefrom.

2. In an adjustable anti-glare device, a pair 40 of oppositely disposed units, a framework disposed intermediate the said units, a vertical member arranged adjacent the front of the said framework, means whereby the aforesaid units are pivotally connected to the said framework and vertical member for the purpose of rendering the device susceptible to focus suitable to the eyes.

3. In a device of the character described, a 45 framework and a vertical member for the device,

a portion formed upon the top of the said member, extending forwardly and at right angles thereto, a flexible band and a metal strap for the device and one end pivotally secured to the said extending portion and the opposite end thereof secured to said flexible band, the said strap adapted to conform to the top of the head, and the said band adapted to hold the device upon the head.

4. In a device of the character described, a 50 pair of oppositely disposed metallic units having an inner wall, a vertical member disposed intermediate the said units, the metal of the inner wall of the said units adjacent the said member being formed at right angles thereto and forming thereby a shield for preventing the light from blinding the eyes.

5. In a device of the class described, a pair 55 of oppositely arranged units having a top surface, a vertical member intermediate the said units, a horizontally extending portion upon the top of the said member, a lever pivotally secured to the underneath surface of the said portion, a stop formed upon each end of the said lever, a link pivotally secured to each end of the said lever and the opposite ends of the said links being pivotally secured to aforesaid top surface of the units respectively, and in order to render the same adjustable relative to the aforesaid vertical member.

6. In an adjustable anti-glare device, a pair 60 of opposed units, each having an outer vertical wall, means within the said units for passage of vision therethrough, means within the same for preventing the light through the said passage from reflecting upon the inner surface of the outer vertical wall of the said units, and further means within the said units effecting a shield to prevent blinding the eyes from the glare of the light; a vertical member and framework adjacent the rear of the same intermediate the aforesaid units, means whereby the said units are adjustable relatively to the said vertical member and framework, means upon the 65 top of the said member for supporting the last-named means, also means for supporting the device upon the head and for retaining the same thereupon in a fixed and focused manner.

EDWARD M. KELLER.
